UNITED STATES PATENT OFFICE.

FREDERIK G. WHITTINGTON, OF EVANSTON, ILLINOIS, ASSIGNOR TO STEWART-WARNER SPEEDOMETER CORPORATION, OF CHICAGO, ILLINOIS, A CORPORATION OF VIRGINIA.

DESIGN FOR A VEHICLE SEARCHLIGHT BRACKET.

Application filed February 13, 1922. Serial No. 684. Term of patent 14 years.

To all whom it may concern:

Be it known that I, FREDERIK G. WHITTINGTON, a citizen of the United States, residing in Evanston, in the county of Cook and State of Illinois, have invented a new, original, and ornamental Design for Vehicle Searchlight Bracket, of which the following is a specification, reference being had to the accompanying drawings, forming a part thereof.

In the drawings:—

Figure 1 is a front elevation of a vehicle searchlight bracket embodying my new design.

Figure 2 is a top plan view of the same.

I claim:—

The ornamental design for a vehicle searchlight bracket, substantially as shown.

In testimony whereof, I have hereunto set my hand at Chicago, Illinois, this 9th day of February, 1922.

FREDERIK G. WHITTINGTON.
